OSSIAN HIVELY, OF ALLIANCE, OHIO.

REVERSING MECHANISM FOR VALVES.

Application filed September 10, 1924. Serial No. 736,944.

To all whom it may concern:

Be it known that I, OSSIAN HIVELY, a citizen of the United States of America, and resident of Alliance, county of Stark, and 5 State of Ohio, have invented certain new and useful Improvements in Reversing Mechanism for Valves, of which the following is a specification.

This invention relates broadly to reversing valves for furnaces, and more specifically to reversing mechanism for the valves of regenerative heating furnaces.

The primary object of the invention is to provide a simple and improved form of 15 apparatus or mechanism whereby is effected the necessary preliminary elevation of the reversing valve structure of a regenerative furnace for breaking the water seal, followed by shifting movement of the valve for opening and closing the parts to reverse the direction of the air and gas currents.

A further important object is to provide valve reversing mechanism of the character referred to which effectually guards against over-travel of the valve in the reversing movements of the latter.

With these and other important objects in view, the invention resides in the features of construction, arrangement of parts and 20 combinations of elements which will hereinafter be fully described, reference being had to the accompanying drawings, in which—

Figure 1 is a top plan view of the invention with parts of the structure omitted;

Figure 2 is a sectional elevation of the same, the section being taken substantially on the line 2—2, Fig. 1;

Figure 3 is an end elevation of the same;

Figure 4 is a detail section of the outer 40 end of the valve-lifting portion of the mechanism, showing the crank arm rotated forward throughout one-quarter of a revolution preliminary to effecting reversing movement 45 of the reversing valves;

Figure 5 is a similar view showing the lower pawl in underlying seated relation to the lifting arm;

Figure 6 is a similar view showing the 50 position assumed by the parts following shifting of the valves in one direction to reversed position;

Figure 7 is a top plan view of the invention, illustrating its application;

Figure 8 is a sectional elevation; and—

Figures 9 and 10 are diagrammatic views of the valves illustrating the two opposite positions assumed by the valves with respect to the various ports.

Referring to said drawings, 1 indicates generally the usual form of bearing employed in an ordinary type of valve reversing mechanism which includes an upright post-like support 2 carried by the rotary member 1^a of the bearing. Fulcrumed upon the post 2 is the outer end of an arm 3 which is fixed to a horizontally disposed pin 4 journaled in supports 5 fixed to a main frame 6. Said main frame 6, which is rotatable about and vertically movable with respect to the supporting structure 7 for the bearing 1, carries thereon a hood-like valve 8 of arcuate form designed to be shifted for effecting reversal of the travel of air and gas currents with respect to the regenerators (not shown). Said bearing 1 is located centrally with respect to a circular arrangement of air and gas ports with vertical descending flues connecting with the air and gas regenerators. As ordinarily, there are employed two sets of air and gas ports arranged at opposite sides of a port 9 opening into a stack flue, as shown in Fig. 7, wherein the air and gas at one side are designated 10 and 11, respectively, and the air and gas ports at the other side are designated 10' and 11', respectively. The valve 8 at one limit of its shifting movement overlies the air and gas ports 10 and 11 and the stack-flue port 9, providing passage to the stack for outgoing products of combustion. At the same time, a hood-like valve member 12 carried by the main frame occupies a position wherein it constitutes a duct for the passage of ingoing gas from the gas producers to the regenerators, being disposed to connect port 11' to the centrally located overhead producer flue 13. At the opposite limit of movement of the valve mechanism, the valve 8 overlies and provides passage from ports 10' and 11' to the stack-flue port 9, while the valve member 12 connects port 11 to the overhead producer flue 13.

Power for elevating and rotating the reversing valve structure between the positions indicated is supplied by an electric motor 14 which operates through suitable gearing to rotate a horizontal shaft 15 journaled in a stationary portion of the base structure.

Fixed on said shaft is a cam 16 upon the periphery of which rides a roller 17 carried by an intermediate portion of a lever 18. Provided in the outer end of said lever is 5 an open longitudinally extending slot 19 in which is received a portion of the shaft 15 located adjacent to said cam 16. Said lever, which normally occupies an inclined position, as shown in Fig. 8, has its opposite end 10 pivotally connected to an upwardly and outwardly inclined arm 20^a formed on a lever 20 which is rigidly mounted on the pin 4 and which carries upon its free end a balance weight 21.

15 In their normal positions the valves 8 and 12 are seated in trough-like water-containing channels 38 forming water-seals. Consequently, said valves must be elevated to a height affording clearance therefor prior 20 to shifting movement for effecting reversal thereof. Such elevating movement is effected in the first quarter revolution of the shaft 15, the cam 16 acting through the roller 17 to thrust inwardly the lever 18 which, 25 in turn, produces elevation of the arm 20^a, pin 4 and the thereto-attached main frame 6 and the valves 8 and 12 to the extent required, said parts being elevated upon the fulcrum constituted by the post 2.

30 The first quarter revolution of the shaft 15, above referred to, carries a crank-arm 22 which is fixed to said shaft from its normal vertically depending position, shown in Fig. 2, to the horizontal position shown in 35 Fig. 4, wherein its outer end portion directly underlies the end of a pawl 23 which is pivotally mounted upon a pin 24 carried by the upper end of a link 25. Said link is rigidly carried upon the outer end of an 40 arm 26 which is loosely mounted upon the shaft 15. The pawl 23 is constituted by one arm of a bell-crank lever of which the opposite arm 27, herein termed a dog, rests upon the free end of a leaf spring 28 which has 45 its opposite end pivoted at 29 upon the shaft-embracing end of the arm 26 and which is fulcrumed intermediate its ends upon an upright lug 30 formed on an intermediate portion of said arm 26. Said spring 28 50 normally maintains the said bell crank in the position shown in Figs. 2, 4 and 5, wherein the pawl 23 is disposed in the path of rotary travel of the crank-arm 22. Thus, 55 continued travel of said crank-arm beyond the first quarter revolution thereof produces elevation and travel therewith of the link 25 and arm 26, the latter turning on the shaft 15 as an axis.

60 A pin 24' carried by the opposite end of the link 25, which end is lowermost, as shown in Figs. 2, 4 and 5, has mounted thereon a bell-crank similar to that described as mounted at the opposite end of the link, the same forming a pawl 23' and a dog 27'. 65 In the position shown in said Figs. 2, 4 and 5, the dog 27' rests upon a seat or stop 31 formed on one end of a bracket 32 carried by the main frame 6. The weight of the superposed parts being sustained by said dog 27', the same is caused to be elevated 70 against the pressure exerted by its spring 28', similar to spring 28, and the pawl 23' is resultantly swung back a distance sufficient to afford clearance for the crank-arm 22, as shown in Fig. 4. As the crank-arm 75 22 is rotated clockwise from the 90° position shown in Fig. 4, it carries therewith the arm 26 and the mechanism borne by the latter to the reversed position shown in Fig. 6. In the initial part of said movement, the 80 weight supported through the dog 27' is lifted off the latter, allowing the spring 28' to swing the pawl 23' into underlying relation to said crank-arm, as shown in Fig. 5. At the approach to the limit of the clockwise 85 movement of said mechanism, the dog 27 seats upon a stop 31' located at the end of the bracket 32 opposite the stop 31, and the weight of the then lowering parts acts to swing the bell-crank, of which said dog 27 90 and the pawl 23 constitute parts, to the position shown in Fig. 6, in which position said pawl 23 is withdrawn from underlying relation to the crank-arm, allowing the latter to complete its revolution to the vertical 95 position shown in Fig. 2, during which the valves are lowered into their channels for forming water seals.

A laterally extending wrist-pin 33 is carried by the outer end portion of the arm 100 26, and pivotally mounted on said wrist-pin is an end of a connecting rod 34 which has its opposite end mounted in like manner upon a pin 35 carried by the adjacent end of a horizontally disposed rack bar 36 which 105 is slidably mounted upon a guide-member 6^a formed on the main frame 6. Said rack-bar has the teeth thereof operatively engaged with the teeth of the gear segment 37 which is fixed upon the upper part of the stationary support.

In practice, when the main frame and the thereby-supported valves 8 and 12 have been elevated, as hereinbefore described, to a 110 height providing clearance therefor with respect to the water-seal channel portions of the structure, the arm 26 and the thereby-carried link mechanism are swung or rotated throughout an arc of approximately 180°, as hereinbefore described. In said 115 rotary movement, the connecting rod 34 is moved longitudinally, effecting longitudinal sliding movement of the rack-bar 36 throughout the distance required to rotate, through the intermediacy of the gear segment 37 120 and main frame 6, the valves 8 and 12 carried by said frame from the positions shown in Figs. 7 and 9 to the positions shown in Fig. 10.

125 Obviously, the reversal of the valves in 130

counter-clockwise direction is effected by reverse rotation of the motor drive shaft, the operation of the parts being thus reversed.

5 It will be noted that the mechanism described provides for shifting of the valves throughout the required distance only, thereby effectually to prevent overtravel of the valves and to obviate the serious results 10 which such overtravel frequently entails. Furthermore, it will be apparent that continued rotation of the motor following shifting of the valves, due to failure of the motor cut-out to function at the proper 15 time, can have no other effect than to continue the rotation of the crank-arm 22, which rotation is in no way interferred with, the uppermost dog readily yielding in the manner of a ratchet as said crank 20 passes thereby.

What is claimed is—

1. In a reversing valve mechanism for furnaces, the combination with a circular arrangement of air, gas and stack ports 25 having water-seal channels forming valve seats, of a rotary frame carrying valves, a stationarily mounted power shaft, a cam carried by said shaft, means intermediate said cam and said frame whereby rotary 30 movement of the former effects raising and lowering of said frame for seating and unseating said valves, and means whereby said frame is rotated following elevation thereof for shifting said valve in relation 35 to said ports, said rotating means comprising a gear segment carried by said frame, a rack-bar engaged with said gear segment, a crank arm fixed on said shaft, and mechanism intermediate said arm and said rack- 40 bar whereby rotary movement of the former actuates shifting movement of the latter.

2. In a reversing valve mechanism for furnaces, the combination with a rotary valve-carrying frame and means for effecting 45 elevation of said frame, of a gear segment fixed on said frame, a longitudinally shiftable rack-bar operatively engaged with said segment, a power shaft, an arm loosely mounted on said shaft for rotary movement 50 between certain limits, a connecting rod joining said rack-bar to said arm whereby rotary movement of the latter actuates sliding movement of said rack-bar, a crank arm fixed on said shaft, pivoted members carried by said loose arm, springs normally 55 holding said members in the path of rotary movement of said crank arm, and supports adjacent to the opposite limits of movement of said loose arm adapted for having said pivoted members alternately seat thereon and to hold the seated member 60 out of said path of movement of the crank arm.

3. The combination of valves mounted 65 for foward and reverse rotary movements,

a member adapted for rotary movement between certain limits, means intermediate said member and the valve mounting whereby movements of the former effect shifting of the latter, a power actuated crank 70 arm, pivoted elements having mountings in fixed relation to said member, resilient means normally holding said elements in the path of movement of said arm, and stops at the opposite limits of movement of said 75 member, said pivoted elements being alternately pressed out of said path at said opposite limits.

4. In mechanism for effecting the reversal of reversing valve structures, the combination with the valve structure, of a power shaft, means associated with said shaft whereby said structure is elevated in the first part and lowered in the final part of the operating movements of said shaft, a 80 pivotally mounted member rotatable between two opposite limits, means intermediate said member and said valve structure and actuated by movements of the former whereby the latter is shifted from one operative 85 position to the other, a positively rotated member adapted to positively engage said pivotally mounted member during a part of its rotation for carrying the last mentioned member from one limit of movement to the other while said structure remains elevated.

5. In combination with a rotary and vertically movable valve structure, a rotary shaft, means operated by the shaft to move the valve vertically, means to effect rotation 90 of the valve structure including opposed parts, and means carried by the shaft for alternate engagement with said opposed parts to rotate the valve structure in opposite directions.

6. In combination with a rotary and vertically movable valve structure, a rotary shaft, means operated by the shaft to move the valve structure vertically, means to effect rotation of the valve including opposed parts, means carried by the shaft for alternate engagement with said opposed parts to rotate the valve structure in opposite directions, means to engage and hold said means carried by the shaft in predetermined positions, and means to mount the opposed parts whereby upon engagement with said holding means to allow said means carried by the shaft to continuously rotate past the opposed parts.

7. In combination with a rotatable and vertically movable valve structure, means to move the valve structure vertically, means to effect rotation of the valve structure, rotatable means to actuate each of the said means, oscillatory means carried by said rotatable means, means to arrest and hold the oscillatory means in predetermined positions, and means fixed to the rotatable means 125 for alternate engagement with said oscillatory means.

tory means for effecting both clockwise and counter-clockwise movement of the oscillatory means.

8. In combination with a rotatable and vertically movable valve structure, means to move the valve structure vertically, means to effect rotation of the valve structure, rotatable means to actuate each of the said means, oscillatory means loosely carried by the rotatable means, means fixed to the rotatable means to effect oscillation of the oscillatory means, and means to arrest and hold the oscillatory means in predetermined positions.

13. 9. In combination with a rotary and vertically movable valve structure, means to raise and lower the valve structure, means to rotate the valve structure, means to actuate each of said first named means, independent means carried by said actuating means, and means fixed to the actuating means for alternate engagement with said independent means whereby to effect rotation of the valve structure in opposite directions.

10. In combination with a rotary and vertically movable valve structure, means to raise and lower the valve structure, means to rotate the valve structure, means to actuate each of said first named means, independent means carried by said actuating means, means fixed to the actuating means for alternate engagement with said independent means whereby to effect rotation of the valve structure in opposite directions, means to engage and arrest movement of said independent means, and means whereby to allow of continuous movement of the actuating means upon arresting of said independent means.

11. In combination with a rotary and vertically movable valve structure, rotatable means, means actuated by said rotatable means to raise and lower the valve structure, means to effect rotation of the valve structure loosely connected to the rotatable means, means to arrest and hold said valve struc-

ture rotating means in predetermined positions, and means movable with the rotatable means for engaging the valve structure 50 rotating means to actuate same in opposite directions.

12. In combination with a rotatable and vertically movable valve structure, a shaft, means whereby upon turning of the shaft 55 the valve structure will be moved vertically, means connected to the valve structure and loosely connected to the shaft to rotate the valve structure, movable dogs on the said rotating means, means fixed on the shaft 60 and alternately engageable with the dogs to move the rotating means in opposite directions, and stop means alternately engageable with the dogs to arrest the movement of the rotating means and to move 65 the engaged dog to permit said means fixed on the shaft to continue rotating with the shaft without effecting further movement of the rotating means.

13. In combination with a rotatable and vertically movable valve structure, a shaft, means whereby upon turning of the shaft the valve structure will be moved vertically, means connected to the valve structure and loosely connected to the shaft to rotate the 75 valve structure, spaced movable means on the rotating means, means fixed on the shaft and alternately engageable with the spaced means to move the rotating means in opposite directions, and arresting means alternately engageable with the spaced means 80 to arrest the movement of the rotating means and to move the arrested one of the spaced means to permit the means fixed on the shaft to continue rotating with the shaft without effecting further movement of the rotating means.

In testimony whereof, I affix my signature in presence of two subscribing witnesses.
